UNITED STATES PATENT OFFICE

ELLSWORTH T. JOHNSON, OF MOLINE, ILLINOIS, ASSIGNOR TO DEERE & COMPANY, OF MOLINE, ILLINOIS, A CORPORATION OF ILLINOIS

BUNDLE CARRIER

Application filed June 17, 1931. Serial No. 544,968.

This invention relates to grain binders and similar farming implements and is more particularly directed to a new and improved form of bundle carrier therefor.

5 One of the features of the present invention is to provide a bundle carrier arranged to carry enough bundles at any one time to build a normal size shock. In this way the labor of shocking the bundles of grain is 10 materially reduced in that it is not necessary for the shockers to manually pick up the bundles and carry them to the shock. To this end a bundle carrier is provided having one end supported on the binder frame 15 for free pivotal movement in a transverse vertical plane of the binder and also having horizontal swinging movement, and which is supported at its other end on a ground wheel. In this manner the carrier is not entirely 20 supported at its binder end as contrasted with hereinbefore existent carriers for binders, wherein the whole unit is suspended outwardly from the binder and whereby all of the weight thereof must be sustained by the 25 suspension means and by the binder.

It is also one of the important features of the present invention to provide a bundle carrier which is supported at its outer end on a wheel and which is capable of having 30 unlimited pivotal movement in a vertical direction and also capable of swinging rearwardly when it strikes an obstruction.

By utilizing a carrier having a pivotal connection with the binder for unlimited 35 movement in a transverse vertical plane and having its outer end supported on a wheel, the carrier will, under the usual operating conditions, be maintained substantially parallel to the ground when the binder is 40 traveling over undulations in the ground. Furthermore, the present carrier is so arranged that when it swings horizontally after striking an obstruction the vertical movement about its binder connection in a 45 transverse vertical plane is not interfered with.

Another object of the present invention is to provide a carrier having a positive latch mechanism for holding the same in trans- 50 verse alignment with respect to the binder

frame under normal operating conditions. This latch mechanism will hold the carrier in operating position at all times, but is automatically releasable to allow the carrier to swing horizontally when an obstruction, 55 such as a post or other stationary object, is encountered. Heretofore it has been the practice to hold the carriers in substantially transverse alignment with respect to the binder by means of tension springs, but that 60 method has proven to be objectionable because the carrier has a tendency to drag rearwardly upon becoming fully loaded. This is particularly true for larger carriers 65 which are adapted to carry a large number of bundles. By utilizing a latch mechanism of the present construction in connection with a carrier, this objectionable feature has been remedied to enable large carriers to be employed on grain binders and the like. 70

Another feature of the present invention is the provision of a carrier having means whereby the carrier supporting wheel is always maintained in longitudinal alignment with respect to the line of forward advance 75 of the binder, even when the carrier swings rearwardly upon striking an obstruction. This prevents undue stresses in the carrier structure which would otherwise occur if the outer supporting wheel were not held to 80 travel in the direction of the binder and were forced to skid.

Other features and advantages will hereinafter appear in the following detailed description of a preferred embodiment of the 85 invention having reference to the accompanying drawings.

In the drawings:—

Figure 1 is a plan view of the carrier illustrating the manner in which it is connected with a binder frame, the carrier being shown in its normal operating position in transverse alignment with respect to the binder; 90

Figure 2 is a plan view of the carrier corresponding to that shown in Figure 1 but illustrating the same when it is swung rearwardly, as upon striking an obstruction; 95

Figure 3 is a vertical cross-sectional view 100

taken substantially along the plane of line 3—3 in Figure 4;

Figure 4 is a front elevational view of the carrier mounting on the binder frame as seen when looking rearwardly and showing that portion of the carrier which is viewed along line 4—4 in Figure 1; and

Figure 5 is a detailed cross-sectional view illustrating the universally pivotal connection of the carrier with the binder.

The bundle carrier embodying my present invention is of the same general construction as the carrier disclosed in the patent to Robert C. Livesay, No. 1,597,986, issued August 31, 1926, over which the present construction is an improvement. The preferred embodiment of bundle carrier illustrated in the drawings comprises a frame 6 having one end mounted on the binder frame 7 by means of the new and novel supporting mechanism 8 for unlimited pivotal movement in a transverse vertical plane, for fore and aft tilting movement and for swinging movement in a horizontal plane, the other end of the carrier being supported by a ground wheel 5.

The frame 6 constitutes a pipe 9 having crank arm 10 secured within one end thereof and a wheel axle 11 pivotally mounted at 4 on its other end, and a bar 12 suitably connected with the pipe for shifting movement relative thereto, by means of links 13 and 14. Link 13 is secured to a fixed bracket carried by the wheel axle 11 and link 14 is pivotally connected with the pipe, while both of the links are pivotally connected with bar 12 at 15 and 16, respectively, to form a parallelogram frame construction. The carrier fingers or tines 17 carried by the frame 6 have downturned forward ends pivotally connected with bar 12 which are held in place by cotter pins or the like, and the tines are supported intermediate their lengths by bifurcated brackets 18 which are swiveled to the pipe 9. Suitable guard tines or rods 19 are likewise pivotally connected at 20 with bar 12 and supported intermediate their ends by brackets 22 swivelly mounted on pipe 9, thus acting as a means for retaining the bundles of grain laterally upon the tines 17 until they are discharged therefrom. Another guard or rod 23 is secured to bar 12 and extends transversely across the forward portion of the carrier to keep the bundles from dropping over the front edge thereof. Suitable table members 24 and 25 are connected with pipe 9 and bar 12, respectively, to move therewith, and function as guard plates to prevent the bundles on the carrier from dropping into the spaces between the tines or between the bars 9 and 12, since that would interfere with the folding action of the carrier as it is forced to swing rearwardly.

65 The crank arm 10 is rotatably carried in

a longitudinally extending sleeve 26. A collar 27 is welded or otherwise secured to one portion of the arm 10 and abuts one face of the sleeve 26, the collar being so positioned on the arm as to allow the latter to project beyond the other face of the sleeve to receive another sleeve or socket member 28. The latter is secured to the arm for movement therewith by means of a pin 29 and the member 28 has a flattened end 30 for 70 accommodating suitable bracing rods 31 and 32. The carrier brace rod 31 has one end thereof loosely connected for universal movement with the flattened end 30 of the sleeve and has its other end pivotally inserted in a bracket 33 connected with the pipe 9. The sleeve 28 is braced by means of the rod 32 which has a pivotal connection with the end 30 thereof and a connection with a bracket element 33a of the mounting mechanism. From the foregoing explanation it is seen that the whole carrier unit is capable of free pivotal vertical movement on its pivotal connection by means of arm 10 within sleeve 26 and by reason of the fact that the brace rods 31 and 33 have pivotal connections with sleeve 28.

The binder frame 7 is provided with laterally extending bars 34 and 35 which are spaced apart for receiving the reduced ends or spindles 36 of a substantially vertically disposed bracket 37. Bracket 37, preferably a casting, is thereby mounted for pivotal movement about a substantially vertical axis and is provided with a laterally extending sleeve 38 best illustrated in Figure 5. The outer end of the sleeve 38 is enlarged as at 39 to form a socket for rotatably harboring a sleeve 40 therein. The latter may be secured to, but preferably formed integrally with, the longitudinal sleeve 26 and by means of this pivotal connection the carrier is capable of being tilted about a transversely extending axis to dump the bundles therefrom.

The carrier dumping mechanism may be of any well known construction. In this form of carrier it consists of an operating rod 42 journaled in a bracket 42a and having its crank end 43 connected by means of a laterally and vertically swingable link 44 with an arm 45 which is pivotally mounted at 45' on the bracket 37. Another connecting link 46 extends between the arm 45 and a suitable fitting 47 having a straddling connection with the bent portion of crank arm 10 in the manner best shown in Figures 1 and 3. By rocking the operating rod 42 in a clockwise direction as viewed in Figure 3 motion is transmitted through the above described elements to the crank arm which in turn allows the carrier to drop from bundle carrying position to dumping position and vice versa, about the pivotal connection of sleeve 40 within socket 39. As best il-

lustrated in Figure 3, the arrangement of the parts 42, 42a, 43, 44 and 45 is such that the bundle carrier is held up by virtue of a toggle connection established between the 5 arm 43 and the link 44.

One end of a spring 48 is adjustably connected with the binder frame 7 at 49 and the other end thereof is connected with a depending arm 50 secured to a shaft 52 having 10 pins 53 connecting the same with sleeve 40. By means of this connection the spring 48 exerts its force through the arm 50 to the inner end of the laterally extending sleeve 38 to swivel the bracket 37 and the balance 15 of the carrier elements in a horizontal direction about the vertical axis of the spindles 36. As an additional feature it is to be noted that spring 48 also functions to return the carrier from dumping position to 20 bundle carrying position. This function is effected by the action of spring 48 in rotating shaft 52 and crank arm 10 until rotational movement of those elements is halted when link 44 eventually assumes the position 25 shown in Figure 3 as determined by the dead center position of the crank end 43 of rod 42 with respect to link 44. Thus the spring 48 acts not only to return the carrier to its normal transverse alignment 30 with respect to the binder, but also to raise the carrier, and in its latter capacity it also cooperates with the toggle connection 43-44 to hold the carrier in its upper or bundle carrying position.

35 On striking an obstruction, the whole carrier is swingable rearwardly in a horizontal plane into any position, such as the one illustrated in Figure 2, by means of the pivotal connection of bracket 37 with the binder frame bars 34 and 35. When the carrier is so swung, the tension spring 48 further acts to aid in returning the carrier to its normal operating position, namely, in transverse alignment with respect to the binder.

40 The carrier of the present construction has been particularly devised to carry a large number of bundles preferably a sufficient number to build a normal size shock. Under such conditions a carrier depending only on a spring such as 48 to retain the same in normal transverse alignment with the binder is impractical and objectionable since the carrier always tends to drag rearwardly before it is fully loaded. To enable 45 a large carrier to carry a great many bundles an automatically releasable latch mechanism 54 is provided, which will, under all normal conditions, positively retain the carrier in transverse alignment with the binder but which will still allow the binder to 50 swing rearwardly under an abnormal strain, such as would occur should it encounter an obstruction.

55 This latch mechanism constitutes a latching dog 55 yieldingly held in position

against the wide face of frame bar 35 by means of a spring 56, the tension of which is adjustable, as best shown in Figures 1, 2 and 3. The dog is provided with an abutment shoulder 57 engaging one edge of 70 frame bar 35 and with a latch hook 58 disposed in spaced relation to the opposite edge of the frame bar for the reception of a lug 59. The latter is carried by the laterally extending sleeve 38 of bracket 37, and normally depends downwardly therefrom into the space between hook 58 and frame bar 35. The lug 59 prevents forward movement of the carrier beyond its normal operative transverse position relative to the 75 binder by its engagement with latch hook 58. The lug retaining edge 60 of hook 58 is slightly tapered upwardly to properly allow the lug to cam the latching dog downwardly and out of engagement therewith 80 when an obstruction is encountered by the carrier. The forwardly extending edge 62 of hook 58 is beveled to allow lug 59 to snap into place by camming the latch dog downwardly against the action of its spring as 85 the carrier returns to normal operative position.

When the binder is in operation the bundle carrier will be held in the position shown in Figure 1 by the latching mechanism, 90 aided by spring 48 which also exerts its force to hold the carrier in its normal forward position. In this position the carrier has free vertical movement about the axis defined by the fore and aft extending portion of the crank arm 10, by which portion the crank arm is rotatably mounted and carried on the binder frame. If an obstruction is encountered the latching mechanism 95 54 is automatically disengaged, as explained above, to allow the carrier to swing rearwardly against the action of spring 48 which later returns the carrier to its normal operative position.

When the carrier is thus moved rearwardly the whole unit swings about the axis of the vertically pivoted bracket 37. During this action pipe 9 of the frame 6 remains in its same relative position to the bracket, but bar 12 is moved towards the bracket and relatively to pipe 9 by means of a link or rod 63 which has its one end pivotally connected with a clip 64 carried by the bar and its other end pivotally connected with the stationary support 65 on the binder frame. The result is that the parallelogram frame 6 is collapsed or folded and the tines are kept parallel and in fore and aft alignment with the binder, and through the same folding action, bar 12 causes the axle of 110 wheel 5 to revolve on its pivotal connection 4 through link 13, whereby the ground wheel 115 is so moved as to remain in true fore and aft alignment with the binder. Thus objectionable skidding is eliminated and undue 120 125 130

stresses in the carrier elements are prevented.

Although the foregoing description is directed to a preferred embodiment of my invention as illustrated by way of example in the drawings, it is to be understood that I do not wish to be strictly limited thereto but only in so far as the appended claims are so limited.

10. What I claim is:—

1. In combination with a binder, a bundle carrier, and means mounted on said binder for supporting said carrier for horizontal swinging movement, said means having a longitudinally disposed sleeve providing a first pivotal support whereby said carrier is swingable vertically, and a second pivotal means about which said carrier may be tilted into bundle discharging position.

20. 2. In combination with a binder, a bundle carrier, means mounted on said binder and supporting said carrier for horizontal swinging movement, a wheel for supporting the swingable end of said carrier, and pivotal means carried by the aforesaid means and connected with said carrier whereby the wheel supported end of the latter is vertically movable relative to the binder as said wheel travels over undulations in the ground.

30. 3. In combination with a binder, a bundle carrier, pivotal means mounted on said binder for supporting the carrier for horizontal swinging movement, a wheel for supporting the swingable end of said carrier, and means for maintaining said wheel in fore and aft alignment with respect to the binder when the carrier swings about its pivotal means.

40. 4. In combination with a binder, a bundle carrier, pivotal means mounted on said binder for supporting the carrier for horizontal swinging movement, a wheel for supporting the outer end of said carrier, means for maintaining said wheel in fore and aft alignment with respect to the binder when the carrier swings about its pivotal support, and automatically releasable latching means for holding said carrier in transverse alignment with respect to the binder under normal operating conditions.

50. 5. In combination with a binder, a bundle carrier, pivotal means mounted on said binder for supporting the carrier for horizontal swinging movement, and an automatically releasable latching means for holding said carrier in transverse alignment with respect to the binder under normal operating conditions.

60. 6. In combination with an agricultural implement, a bundle carrier, means for connecting said bundle carrier with said implement for universal movement thereon, means for vertically spacing the outer end of said carrier a substantially predeter-

mined distance above the ground, automatically releasable latching means for positively maintaining said carrier in substantial transverse alignment with respect to the implement under normal operating conditions, and means for positively controlling fore and aft tilting of the carrier.

7. In combination with an agricultural implement, a bundle carrier, means for connecting said bundle carrier with said implement for universal movement thereon, wheel means for supporting the outer end of said carrier a substantially predetermined distance above the ground, automatically releasable latching means for positively maintaining said carrier in substantial transverse alignment with respect to the implement under normal operating conditions, means for positively controlling fore and aft tilting of said carrier to discharge the bundles therefrom, and means for maintaining said wheel means in fore and aft alignment with respect to said implement when said automatically releasable means releases said carrier for horizontal swinging movement.

8. In combination with an agricultural implement, a bundle carrier, a frame therefor, a crank arm connected with said frame, and swiveling means mounted on said implement for movement about a vertical axis, said crank arm being connected with said swiveling means for pivotal movement about a horizontal axis, whereby said carrier has horizontal and vertical swinging movements on said implement, and a wheel connected with said carrier for supporting one end thereof in spaced relation to the ground.

9. In combination with an agricultural implement, a bundle carrier, a frame member therefor, a frame supporting member on said implement, pivotal means connecting said members, and latching means for releasably holding said frame member against swinging movement relative to said supporting member under normal operating conditions.

10. In combination with an agricultural implement, a bundle carrier, a frame member therefor, a frame supporting member on said implement, pivotal means connecting said members, and latching means for releasably holding said frame member against swinging movement relative to said supporting member under normal operating conditions and comprising a latch dog yieldingly connected with one of said members, and stop means engageable by said dog and connected with the other of said members.

11. In combination with an agricultural implement including a frame, a bundle carrier swingably supported on said implement, and latch means for releasably holding said carrier in fixed relation to the im-

- plement and comprising a latch dog, spring means for yieldingly mounting said dog on said implement frame, said latch dog having a latch hook disposed in spaced relation to 5 said frame, and stop means connected with said swingable carrier and disposed between said latch hook and said frame, said hook having tapered edges for enabling the stop means to cam the hook out of engagement therewith when said carrier strikes an obstruction and to allow said stop means to snap into engaged position with said latch when said carrier is returned to bundle carrying position, respectively.
- 10 12. In combination with an agricultural implement, a bundle carrier connected with said implement for horizontal swinging movement, a wheel for supporting the carrier, an axle for said wheel pivotally connected with said carrier, and means operable by the swinging movement of said carrier for maintaining said wheel in fore and aft alignment with said implement.
- 15 13. In combination with an agricultural implement, a bundle carrier connected with said implement for horizontal swinging movement, a wheel for supporting the carrier, an axle for said wheel pivotally connected with said carrier, and link means extending between said wheel axle and said implement and operable by the swinging movement of said carrier for maintaining said wheel in fore and aft alignment with said implement.
- 20 14. In combination with an agricultural implement, a bundle carrier, a main frame member therefor connected with said implement for horizontal swinging movement, a wheel for supporting said carrier, an axle for said wheel pivotally connected with said main frame member, an auxiliary frame member disposed in spaced relation to said main frame member, a link connecting said auxiliary frame member with said main frame member, a second link fixedly secured to said wheel axle and pivotally connected with said auxiliary frame member, tines carried by said members and having pivotal connections with each of said members, and 25 means operable by the swinging movement of said main frame member for shifting said auxiliary frame member relative thereto to maintain said tines in parallelism with the implement and to maintain said wheel in fore and aft alignment with respect to said implement and parallel to said tines.
- 30 15. In combination with an agricultural implement, a bundle carrier, a main frame member therefor connected with said implement for horizontal swinging movement, a wheel for supporting said carrier, an axle for said wheel pivotally connected with said main frame member, an auxiliary frame member disposed in spaced relation to said main frame member, a link connecting said auxiliary frame member with said main frame member, a second link fixedly secured to said wheel axle and pivotally connected with said auxiliary frame member, tines carried by said members and having pivotal connections with each of said members, and 35 means operable by the swinging movement of said main frame member for shifting said auxiliary frame member relative thereto to maintain said tines in parallelism with the implement and to maintain said wheel in fore and aft alignment with respect to said implement and parallel to said tines.
- 40 16. In combination with an agricultural implement, a bundle carrier, a frame therefor pivotally mounted on said implement for horizontal swinging movement, a wheel for supporting said frame, an axle for said wheel pivotally connected with said frame for horizontal swinging movement relative thereto, and means for swinging said wheel axle to keep said wheel in fore and aft alignment with respect to said implement when said frame swings relative to said implement.
- 45 17. In combination with an agricultural implement, a bundle carrier, a frame therefor comprising a first member pivotally mounted on said implement for horizontal swinging movement, a second member movable relative to said first member, and means connecting said members comprising an axle element and link means, a wheel on said axle element for supporting said frame, and means extending between said implement and said second member to move the latter relative to said first member as said first member swings horizontally, whereby 50 said axle element is adapted to hold said wheel in fore and aft alignment with respect to said implement.
- 55 18. A bundle carrier for an agricultural implement comprising a carrier frame pivotally mounted on the implement for swinging movement in a horizontal plane, a wheel for supporting the swingable end of said frame, and means for maintaining said wheel in fore and aft alignment with respect to the implement as the same is swung on its implement mounting.
- 60 19. A bundle carrier for an agricultural implement comprising a carrier frame pivotally mounted on the implement for swinging movement in a horizontal plane, and an automatically releasable latching means for holding said frame in transverse alignment with respect to the implement under normal operating conditions.
- 65 20. A bundle carrier for an agricultural implement comprising a carrier frame pivotally mounted on the implement for swinging movement in a horizontal plane, a wheel for supporting said frame, and means piv-

totally connecting said frame and the implement whereby said carrier is vertically rockable relative to the implement.

21. In combination with a binder, a bundle carrier, pivotal means mounted on said binder for supporting the carrier for horizontal swinging movement, and a wheel for supporting the swingable end of said carrier and shiftably connected therewith so as to follow the line of travel of the swingable end of the carrier during the movement of the binder.

22. In combination with a binder, a bundle carrier swingably connected therewith for movement fore and aft relative thereto, wheel means for supporting the outer portion of said carrier, and means connecting said wheel means with said carrier for movement relative thereto about a substantially vertical axis.

23. In combination with an agricultural implement, a bundle carrier connected therewith for universal movement relative thereto, and latch means for releasably holding said carrier in a predetermined position relative to the implement.

24. The combination with a binder, a bundle carrier connected therewith for universal movement relative thereto, and latch means for releasably holding said carrier substantially transversely with respect to the binder under normal operating conditions.

25. In combination with an agricultural implement having a frame member, a bundle carrier frame member connected with the aforesaid member for universal movement relative thereto, and releasable latch means carried by one of said members and cooperating with the other of said members to releasably hold said bundle carrier frame member against movement in one direction.

26. In combination with a frame of an agricultural implement, a bundle carrier, means for supporting said carrier on said frame for universal movement relative thereto, and latch means for releasably holding said carrier against movement in one direction under normal operating conditions, said bundle carrier and said latch means being oppositely disposed with respect to said carrier supporting means.

27. In combination with an agricultural implement, a bundle carrier, a carrier supporting member pivotally mounted on said implement, a sleeve pivotally connected with said supporting member, said carrier being pivotally connected with one end of said sleeve, and brace means connected between the other end of said sleeve and said carrier.

28. In combination with an agricultural implement, a bundle carrier, a carrier supporting member pivotally mounted on said implement, a sleeve pivotally connected with

said supporting member, said carrier being pivotally connected with one end of said sleeve, brace means connected between the other end of said sleeve and said carrier to steady the laterally outer end of the carrier, and brace means connected between said other end of said sleeve and the carrier supporting member to steady said sleeve.

29. In an agricultural implement, a bundle carrier member, a supporting member pivoted on said implement, a sleeve member pivotally mounted on said supporting member and connected with the carrier member, and brace means connecting the aforesaid members to rigidly hold the same in cooperative relation to each other.

30. A bundle carrier for an agricultural implement comprising a carrier frame having one end thereof pivotally mounted on said implement, means supporting the other end of said frame, tines connected with said frame and disposed parallel to the adjacent side of the implement, and means for constantly holding said tines parallel to the adjacent side of the implement regardless of the movements of the carrier frame.

31. The combination with an agricultural implement, a bundle carrier, swivel means mounted on said implement to support the carrier for horizontal swinging movement and providing pivotal means about which said carrier is free to rotate vertically, said carrier having its inner end connected with said pivotal means and its outer end free to move into positions above or below the horizontal plane of its point of connection with said pivotal means, and means connected with the outer free end of said carrier to support the same at a predetermined height above the ground.

In witness whereof, I hereunto subscribe my name this 11th day of June, 1931.

ELLSWORTH T. JOHNSON.
